UNITED STATES PATENT OFFICE.

HIRAM C. PARKER, OF MONTE CREEKE, BRITISH COLUMBIA, CANADA.

FOLDING TENT.

1,051,252.

Specification of Letters Patent. Patented Jan. 21, 1913.

Application filed April 10, 1912. Serial No. 689,922.

To all whom it may concern:

Be it known that I, HIRAM C. PARKER, a subject of the King of Great Britain, residing at Monte Creek, in the Province of 5 British Columbia and Dominion of Canada, have invented new and useful Improvements in Folding Tents, of which the following is a specification.

This invention relates to tents and particularly to a shelter tent for camping purposes.

An object of the invention is to provide a tent which may be constructed of a single piece of canvas or fabric material which may 15 be folded flat so as to assume a very small package for storing or shipping purposes.

Another object of the invention is to provide a tent wherein the companion walls and flaps are accurately defined so as to insure 20 the proper setting up of the tent and to enable one to readily fold the same.

Another object of the invention is to provide a tent which may be either folded flat or folded in roll form and to provide pole 25 attaching ropes which may be secured around the body of the tent when the latter is rolled.

In the drawing forming a portion of this application and in which like letters of reference indicate similar parts in the several views:—Figure 1 is a perspective view of the tent showing the closure flaps in closed position. Fig. 2 is a view similar to Fig. 1 showing the top closure flap and one of 30 the side closure flaps opened. Fig. 3 is a section on line 3—3 of Fig. 1. Fig. 4 is a section on line 4—4 of Fig. 1. Fig. 5 is a plan view of the tent unfolded. Fig. 6 is a perspective view showing the tent folded 35 flat. Fig. 7 is a perspective view showing the tent rolled.

The tent may be formed of fabric material such as canvas and it is constructed of a single piece of material and provided with 45 a top wall 1 of substantially rectangular configuration, the substantially triangular side walls 2, the side closure flaps 3 and a top closure flap 4. The top wall 1 and the side flaps 2 of the tent are gathered longitudinally and fold defining seams 5 are made therein as clearly shown. A similar fold or defining seam 6 is formed in the material between the front of the top wall 1 and the inner portion of the top closure flap 4. A 50 rope is secured in the seam 6 and the terminals 8 thereof are extended beyond the sides.

of the flap 4 for a purpose to be hereinafter described. With a view to reinforcing the side walls 2 and for maintaining the shape 60 of these walls they are stitched as at 9.

Incident to the peculiar configuration of the blank, the tent, when set up as shown in Figs. 1 and 2 of the drawings is of an increasing height toward its front end. The tent is relatively narrow and is designed to 65 completely shelter a cot or like bed forming object. The sides 2 are provided with a longitudinal series of eyelets 10 through which stakes may be passed and driven into the ground to effect a proper anchorage of 70 the tent. The lower end of the wall 1 is provided with a similar series of eyelets 11 which are also designed to receive stakes or similar anchoring devices as shown. The side closure flaps 3 at the front of the tent 75 are provided in their lower corners with eyelets 12 which are also adapted to receive anchoring stakes. The upper corners of the flaps 3 are provided with cords 13 which may be tied together when it is desired to 80 effect a closing of the tent at the front thereof. Seams 14 are formed in the tent material at points between the walls 2 and the side closure flaps 3 so as to define the proper 85 lines of fold between the said walls 2 and the said side flaps.

When it is desired to pack the tent for shipment and to arrange the same in a flat package the side flaps 3 are folded against the side walls 2. The walls 2 are then 90 folded on each other so as to lie against the main top wall 1 of the tent. The flap 4 is then folded onto the walls 2 and the tent folded to assume the package shown in Fig. 6. If it is desired, the tent may be rolled 95 as shown in Fig. 7 and at such time the cord terminals 8 are wrapped around the roll and tied as at 15, thereby maintaining the proper shape of the roll and insuring against the unrolling of the tent while in shipment. 100 The poles 16 at the open front end of the tent are engaged at their upper ends against the top wall 1 and the cord terminals 8 are tied around the poles as shown in Fig. 2.

The closure flaps 3 have their upper surfaces 3^a inclined downwardly away from the adjacent front portion of the top wall of the tent, whereby the same adjacent portion of the top wall and the edges 3^a define the space immediately at the front upper end of 105 the tent. This construction is such that the side closure flaps 3 can be closed together 110

and securely connected one with the other through the medium of the cords 13, while the flap 4 can be folded over to the position shown in Fig. 1, whereby to close the space. 5 If desired, the flaps 3 may be held together and the flap 4 folded over against the top of the tent when it is desired to ventilate the tent but to practically house the same by the front of flaps 3.

10 I claim:—

A tent constructed of a single piece of material and provided with a top wall of the same width throughout its length, side walls of substantially triangular configuration, closure flaps adapted to be folded over each other and provided with overlapping

free portions whose upper edges extend downwardly from the adjacent portion of the top wall, whereby to define a space between the top wall and the closure flaps, and 20 a closure flap carried by the said top wall and adapted to be folded over against the upper portions of the closure flaps of the side walls and to cover the said intervening space between the closure flaps of the side 25 walls and the said top wall.

In testimony whereof I affix my signature in presence of two witnesses.

HIRAM C. PARKER.
